DESIGN FOR A SUIT ENSEMBLE

Abraham Breitman, New York, N. Y.

Application February 13, 1939, Serial No. 82,956

Term of patent 3½ years

To all whom it may concern:

Be it known that I, Abraham Breitman, a citizen of the United States of America, residing in New York city, in the Borough of Manhattan, county and State of New York, have invented a new, original, and ornamental Design for a Suit Ensemble, of which the following is a specification, reference being had to the accompanying drawing, forming part thereof, wherein—

I claim:

The ornamental design for a suit ensemble, substantially as shown.

ABRAHAM BREITMAN.
